Atty's:

UNITED STATES PATENT OFFICE.

BERNARD G. KLEIN, OF CHICAGO, ILLINOIS.

METHOD OF MAKING EMBOSSED DESIGNS.

Application filed August 2, 1928. Serial No. 296,969.

The main objects of this invention are to provide an improved method of producing embossed lettering or designs; and to provide an improved method of applying a fusible material such as sealing wax to a supporting panel for producing an embossed advertising card or other sign which is decorative.

An illustrative embodiment of certain means for carrying out this improved method 10 is shown in the accompanying drawing, wherein:—

Figure 1 is a perspective of four matrix blocks supported on a base panel for receiving the fused sealing wax from an applicator.

15 Fig. 2 is an enlarged transverse section taken on the line 2—2 of Fig. 1 and showing the sealing wax after it has congealed.

Fig. 3 is an enlarged detail in perspective showing a portion of the embossed matter.

20 Embossed advertising display cards and other signs have been made commonly with sealing wax applied to a receiving sheet or card. Waxes of different colors have been used for the letters or other designs.

25 Heretofore, the process of making such embossed designs has been performed entirely with a hand operated writing instrument, from which the melted wax flowed directly onto the receiving sheet without the use of a

30 matrix. The instrument was used somewhat like a fountain pen. In view of the fact that it was all free hand work, the prior method was slow and expensive, required skilled operators and artists and no two pieces of work 35 were identical. The prior method was, therefore, impractical for quantity production.

40 My improved method of producing embossed designs includes the use of a matrix adapted to be placed on the base panel for receiving the melted wax. The matrix is made of a material, preferably metal, to which sealing wax will not adhere and the back thereof is open and unrestricted so that the top surface of the sealing wax is permitted to form a 45 natural convex meniscus, which clearly distinguishes the design from one having molded characters.

When liquid comes in contact with a solid which is moistened by it, the liquid is raised 50 upwards against the sides of the solid and its surface, instead of being horizontal, is slightly concave, forming a concave meniscus. If, on the contrary, the solid is one which is not moistened by the liquid, the liquid is depressed against the sides of the solid and as-

sumes a convex shape, forming a convex meniscus.

When melted sealing wax comes in contact with metal and the surface of the liquid is not confined by a top or cover, it forms a natural 60 convex meniscus.

The improved matrix may comprise a single block for each design or a plurality of separate blocks each of which contains a portion of the design as, for instance, a single 65 letter.

In the form shown in the drawings, a plurality of separate matrix blocks 1 are supported on a base 2 for receiving a fused medium, such as sealing wax from an applicator 70 3 or other suitable device.

The blocks 1 are made of metal or any other suitable material to which the fusible medium will not adhere and the base 2 may be made of paper, card-board, wood or other material 75 to which wax will adhere.

The letters or other characters extend through the block, so that the back of each block is open and unrestricted. Certain letters, such as "R", require bridge portions 4 80 to support an intermediate part, such as the part 5. Sufficient draft is provided in each matrix to permit the block to be readily withdrawn after the wax has set.

The applicator 3 may be of any desired construction. In the form shown, it includes a magazine 6 adapted to contain the sealing wax, which is ejected through a nozzle 7 controlled by a valve mechanism 8. An electric heater 9 is provided for heating the wax. 90 The magazine is supported on an arm 10 pivoted to a link 11, which is rotatably mounted on a standard 12, whereby the nozzle 7 may be manually shifted to any desired position over the blocks 1.

In carrying out this improved method, the base 2 is placed in a horizontal position on a table or other support, on which the standard 12 is mounted. The matrix blocks 1 are then placed in the desired position on the base 2. 100 The operator then moves the applicator nozzle over each letter and opens the valve mechanism thereby permitting the melted wax to flow through the open back of each matrix to form the letters 13.

When the sealing wax comes in contact with the metal walls of the matrix, the top surface of the wax forms a natural convex meniscus 14, which gives the finished design 110 an appearance which is exceedingly attrac-

tive. After the wax has hardened, the matrix blocks are removed for further use.

It will be understood that details of the construction shown may be altered or omitted and steps in the method varied without departing from the spirit of this invention as defined by the following claims.

I claim:

1. The method of making embossed designs which consists in providing a fusible medium and a base to which said medium will adhere, placing upon the base a matrix having an unrestricted open back and defined by walls to which said medium will not adhere, introducing the fused medium through the back of said matrix, allowing said medium to con-

geal with convex meniscus, and then separating said matrix and base.

2. The method of making embossed designs which consists in providing a base to which sealing wax will adhere, placing upon the base a matrix having an unrestricted open back and defined by walls to which said sealing wax will not adhere, introducing fused sealing wax through the back of said matrix, allowing said wax to cool so as to congeal with a convex meniscus, and then separating said matrix and base. 25

Signed at Chicago this 26th day of July 1928.

BERNARD G. KLEIN.
